UNITED STATES PATENT OFFICE.

PENTECOST J. MITCHELL, OF DRAGOON SUMMIT, ARIZONA TERRITORY,
ASSIGNOR OF ONE-HALF TO SAMUEL H. ECKLES, OF SAME PLACE.

HOISTING APPARATUS.

SPECIFICATION forming part of Letters Patent No. 292,244, dated January 22, 1884.

Application filed November 12, 1883. (No model.)

To all whom it may concern:

Be it known that I, PENTECOST J. MITCHELL, of Dragoon Summit, in the county of Cochise, Arizona Territory, have invented a new and Improved Hoisting Apparatus, of which the following is a full, clear, and exact description.

My invention relates to hoisting apparatus used about mines for raising the ore to the surface of the ground, and known as "hoisting-whims;" and the object of the invention is to provide a simple, durable, efficient, and inexpensive apparatus of this character.

The invention consists in a contrivance of the drum-shaft, to be lifted with its bearing at one end for disengaging the gear on the drum-shaft from the driving-gear on the main vertical shaft, to which the power is applied, together with a friction-brake device to control the lowering load when the gears are disconnected, the whole making an easily-worked machine, especially adapted for safe operation by horse or other animal power, all as herein-after fully described and claimed.

Reference is to be had to the accompanying drawings, forming part of this specification, in which similar letters of reference indicate corresponding parts in both the figures.

Figure 1 represents my improved hoist in side elevation; and Fig. 2 is an end elevation, with parts in section on line *xx*, Fig. 1.

I provide a substantial frame of sill-timbers, *a*, uprights *b*, braced to the sills at *c*, and a cross-bar or head-plate, *d*, in which frame, and at about the center of plate *d*, I journal in any approved way the upper end of a strong post or drive-shaft, *e*, which takes its lower end bearing in one of the timbers of a strong frame, *f*, which supports the hoisting-drum *g* in bearings fitted in the braced uprights or posts *h* of the frame, as shown. The bearing *i* for the shaft *j* of the drum *g* at the end farthest from the drive-shaft *e* does not lift on or in its post-support *h*, while the bearing *k* of shaft *j* next the shaft *e* is fitted in a pair of posts, *h*, so as to slide up and down in these posts to carry the bevel-gear wheel *l*, fixed to the drum-shaft *j*, out of gear with the drive gear-wheel *m*, fixed to the main vertical driving-shaft *e*.

To disengage the gearing *l m*, I employ a

foot-lever, *n*, strongly pivoted at *o* in one of the uprights *h*, and having a bar or rod, *p*, connecting the short arm of the lever with the bearing *k*, which may be lifted by a downward pressure on the foot-plate *q* at the end of the long arm of the lever *n*, as will be readily understood.

For regulating the movement of the drum *g* while lowering the empty cage or other load, I employ the usual friction-band, *r*, having a hand-lever, *s*, by which to press it on the periphery of the drum.

The levers *n* and *s* are relatively located with each other to easily be operated by a single attendant without leaving his place.

The operation is as follows: The horse or other animal power is applied to a sweep, *t*, fixed to the shaft *e*, any suitable track or floor, *u*, being provided for the animal to travel upon. The lever *n* being in normal position and the gears *l m* engaged with each other, the revolution of shaft *l* will wind the hoist-rope *v* on the drum *g* to lift the bucket, cage, or other load attached at the free end of the hoist-rope. When lowering the bucket, cage, or other load, the lever *n* is worked by the foot of the attendant to disengage gears *l m*, the brake-lever *s* being held in readiness to press the brake-band *r* on the drum *g*, as required to properly regulate the lowering of the load. It is evident that this disengagement of gears *l m* and action of the brake *r* relieves the animal of the labor of backing and directly supporting the lowering load by the breech-straps of the harness, which are so liable to break and cause accidents to the machinery, and time is also largely economized. The sizes of the gears *l m* are relatively proportioned to insure a quick hoist of the load.

Having thus fully described my invention, I claim as new and desire to secure by Letters Patent—

1. A hoisting apparatus made substantially as herein shown and described, consisting of a rope-drum and horse-power, combined and operated as set forth.

2. The arrangement of the geared end of the drum-shaft within a movable journal-box, substantially as herein shown and described,

whereby the geared pinion of the drum is adapted to be thrown in or out of gear with the horse-power driving-wheel, as set forth.

3. In a hoisting apparatus, the combination, 5 with the rope-drum, of a foot-lever for moving the drum-pinion out of gear, and a hand-brake for controlling the motion of the drum, substantially as shown and described.

4. The combination, with the main shaft 10 and gear $l\ m$ and the vertically-adjustable

drum-shaft bearing k , of the lever n , substantially as shown and described.

5. The combination, with the drum g , its shaft j , movable bearing k , and lever n , of the friction-brake $r\ s$, substantially as shown and 15 described.

PENTECOST J. MITCHELL.
